UNITED STATES PATENT OFFICE

CHARLES F. PECKHAM, OF PROVIDENCE, RHODE ISLAND; ISABELLE R. PECKHAM, EXECUTRIX OF SAID CHARLES F. PECKHAM, DECEASED

DIFFERENTIAL VALVE

Application filed April 8, 1926. Serial No. 100,570.

This invention relates to improvements in differential valves, particularly dry-pipe valves, for use with the sprinkler systems of automatic fire-extinguishing apparatus. The improvements are directed especially to that type of valve shown in my prior United States Letters Patent No. 1,613,478, dated January 4, 1927.

One object of the present improvement is to provide a valve of the type specified having a minimum number of parts of simplified construction.

Another object of the improvement is to provide a valve requiring very little machining or finishing on its interior, the valve seats and valve clapper or closure being constructed as separate elements which may be machined and finished apart from the valve body or casing.

Another object of the improvement is to provide a valve of the type specified having its closure or clapper constructed as a loose or separate part without pivoted or hinged joints or other fitted connections.

Another object of the improvement is to provide a valve of compact form, minimum weight, and one which is economical to manufacture.

Further objects of the improvements are set forth in the following specification which describes a preferred embodiment of the invention as illustrated by the accompanying drawings. In the drawings:

Fig. 1 is a vertical sectional view of the improved valve taken on its main axis, and showing the valve-closure in full lines as seated, and in dotted lines as raised off from its seat; and

Fig. 2 is a sectional plan view of the valve taken on line 2—2 of Fig. 1 and showing the valve-closure displaced laterally from its seat.

Referring to Fig. 1 of the drawings, in the present embodiment of the invention the improved valve comprises a body or casing 2 provided with a flanged inlet 3 and an opposite flanged outlet 4 which, as here shown, are substantially concentric with the vertical axis passing through the center of the valve. For the purpose of this description the inlet throat 3 of the casing 2 may be considered as

the supply-chamber of the valve, while its enlarged body portion 5 constitutes the delivery-chamber. The base of the delivery-chamber 5, or, in other words, the bottom wall 6 of the main portion of the valve is inclined 55 to the horizontal, preferably at an angle of from fifteen to twenty degrees. At one side of the main body 2 of the valve is an opening 7 which is surrounded by a flange 8 disposed in a vertical plane. A cover-plate 10 is fitted 60 to the flange 8 and held in place thereagainst by means of suitable bolts 11. Preferably, the cover 10 is suspended from a hinge, not herein illustrated, to adapt it to swing away from the side of the valve when the bolts 11 65 are removed.

The cover 10 takes the form of a vertical plate 12 having a semi-circular pocket-like extension 14 projecting from its side and inclined downwardly therefrom, see Fig. 2, and braced from the main plate by ribs 13. The pocket or extension 14 forms the receptacle or chamber for the gravity-operated clapper or closure 15 which is adapted to slide thereinto when released from its seat in the manner as 75 hereinafter more fully explained.

The valve clapper or closure 15 cooperates with a water-seat and an air-seat which are formed on and constituted in a removable ring or annulus 16 surrounding the inlet 80 throat 3 of the valve casing 2. As shown in Fig. 2, the valve-ring or annulus 16 is preferably constructed as a bronze casting which may be machined to the contour illustrated. As shown in Fig. 1, the bottom of the annulus or valve-ring 16 is faced off at 17 to adapt 85 it to fit against the finished face 18 on the inclined floor or bottom wall 6 of the valve body 2. Above this face 17 is an annular pocket or channel 19 for receiving nuts 20 screwed onto the ends of studs 21 which project up through the annulus as shown in Fig. 1; the arrangement of the studs and nuts circumferentially of the annulus being illustrated in Fig. 2. The central opening 22 of the annulus 16 is provided at the top with an inwardly projecting flange or lip 23, the inner edge of which forms a reduced water-throat 24, while its upper face 25 forms the water-seat for the closure or clapper 15. 100

On the outer periphery or rim of the annulus 16 is an overhanging flange 27 provided with a reentrant groove or channel 28. The channel 28 is filled with a ring of block-tin 29, 5 the upper face of which is beveled off to form an air-seat 30 which is inclined at a slight angle to the plane of the water-seat 25.

Within the annular channel 19 at one side of the valve-throat is a drip-valve 35 which 10 is adapted to be tripped automatically from an arm 36, see Fig. 2, carrying an adjustable screw 37 at its end which is engaged by the bottom of the clapper or closure 15. The drip-valve 35 is of usual arrangement and 15 therefore needs no further description herein. Suffice it to state that the drip-valve 35 opens when the clapper 15 is seated and is closed automatically when the main valve is tripped.

20 An air-opening 38 is provided on the side of the outlet 4 of the valve-casing for connecting a test gauge; a small inlet 39 is provided in the delivery-chamber 5 for admitting water to prime the valve; and a drain-valve 40 leads from the inlet or supply-chamber 3 of the casing; all of these elements being of the usual arrangement for the purposes as well understood by those versed in the art. A drain-nipple 41 is also provided in the extension or pocket 14 of the cover 10 to drain the water from this part of the valve, a suitable cock, not shown, being applied to the nipple. A smaller drain opening 43 leads from the bottom of the channel 19 in the annulus 16 to drain water collecting at this point, being normally closed by suitable cock, not herein shown.

25 The clapper or valve-closure 15 is preferably constructed in the form of a relatively flat disk which may be a brass or bronze casting. The under side of the disk or clapper 15 is faced off at 45 to adapt it to fit close against the water-seat 25 on the valve-ring or annulus 16. On the top of the disk the metal is cut away in a cylindrical depression 46 to save unnecessary weight, and extending across the depression and screwed to the flat rim 49 at 50 is a strip 48 which provides a handle for the clapper. Outwardly beyond the rim 49 of the disk 15 is an annular depression or channel 51 which further reduces the weight of the clapper, while the annular tapered rim 49 provides a rib or reinforcement to stiffen its central portion 55 which rests against the water-seat 25 on the annulus 16.

30 Referring to Fig. 2 the channel 51 is bridged by suitable radial ribs 54 which further brace and stiffen the clapper. The outermost rim of the disk 15 is beveled off at 53, and fitted thereto is a rubber ring or washer 55 of substantially frusto-conical form in cross-section. The rubber annulus 55 functions as an air-valve, its outer rim being 55 adapted to flex and to fit snugly against the

inclined air-seat 30 of the tin annulus 29. The air-ring 55 is clamped against the beveled rim 53 of the clapper 15 by means of an outer metal ring or annulus 56 secured to the clapper by suitable rivets or screws 57. 70 A clearance is provided between the bottom face of the outer rim of the clapper 15 and the upper face of the valve annulus 16, but formed on this face of the clapper is an annular rim or shoulder 60 adapted to fit within the outer edge of the channel 19 in the annulus 16. This flange or rim 60 engaging with the recessed rim of the annulus 16 provides a detent or locating means for the clapper to hold it in concentric relation with respect to the valve-seats against which it rests; this construction replacing the pin-and-groove detent means for the clapper as illustrated in my prior Patent No. 1,613,478 above referred to. 85

90 Referring to Fig. 2, a relatively flat shelf or web 61 extends downwardly from the rim of the valve-annulus 16 and is provided with a horizontally extending bead or ledge 62 which serves as a rest for the valve-clapper 15 when the latter slides off from its seat on the valve-ring 16.

95 Projecting inwardly from the vertical plate 12 of the cover 10 is a rounded rib or lug 63 which provides an abutment or stop against which the rim of the clapper 15 is adapted to strike when the latter is raised off from its seat. Referring particularly to Fig. 2, a pair of curved ribs or ways project from the interior walls of the valve casing 2 at the top of the delivery-chamber 5. These guides or ways 64 are adapted to engage the circular rim of the clapper to guide it in its movement as it lifts off from the water-seat. As shown in Fig. 1, the curve of the ways 64 is plotted more or less to the shape of a cam whereby as one edge of the clapper is held by the abutment 63 the lifting of its opposite side as it rides along the ways will cause the clapper to slide downwardly to direct it into the pocket 14 in the cover 10. In this manner the clapper is prevented from tilting or riding up at its lower edge so that it cannot turn over or move into such position as to block or obstruct the outlet 4. 100 110 115

120 At the bottom of the pocket 14 in the cover 10 is a mushroom shaped element 65 constructed of lead or other soft metal and having its stem inserted in a hole 66. The hole 66 is drilled clear through the bottom of the pocket and a screw plug 67 is inserted thereto from the outside to close the opening. The mushroom plug 65 acts as a buffer to protect the rim of the clapper from injury when the latter drops down into the pocket. 125

130 The method of operation of the improved valve is as follows: Under normal conditions the clapper 15 is seated on the valve-annulus 16, with its annular rim or shoulder 60 engaging the edge or rim of the recess 19 in the

seat-ring. In this position the bottom of the clapper rests against the water-seat 25 to close the supply-throat of the valve; while the flexible annulus 55 rests against the air-seat 30 on the outermost rim of the annulus. 5 As with the valve illustrated and described in my prior Patent No. 1,613,478 above referred to, the present valve operates on the differential principle, that is, with a lesser 10 pressure acting upon the greater area on the delivery side of the clapper maintaining the clapper closed against the greater pressure acting upon the lesser area within its water-seat on the supply side. As before noted, 15 the present improved valve is designed for use particularly with dry-pipe systems in which there is no water in the sprinkler pipes when the valve is closed. It is the usual practice, however, to prime the valve 20 with a small quantity of water which is admitted to the delivery-chamber 5 of the casing 2 through a suitable by-pass or funnel connected to the opening 39. The water acts to make a better seal for the air-seat and 25 prevents the annulus 55 from becoming hard and dry and losing its flexibility.

With the valve closed in the manner as above explained air is pumped into the system at a pressure of approximately one-sixth 30 of the service pressure plus fifteen pounds, whereupon the city service gate is opened and the valve is set for operation. When one or more of the sprinkler heads in the system is 35 opened the pressure in the delivery chamber 5 is relieved or reduced to normal atmospheric pressure, whereupon the water-head on the under side of the disk or clapper 15 will raise the latter off from its seat sufficiently to release its rim 60 from the annular edge of the ring 16. Ordinarily the 40 clapper will be raised off from its seat only a slight distance, for as the water commences to flow across the edge of the water-seat 25 the pressure heads in the supply-chamber 45 and delivery-chamber undergo a change in value. In other words, there is a loss of pressure head under the clapper 15 so that it will not be forced violently upward or shot away from its seat-ring.

50 As the clapper 15 is raised off from its seat the action of gravity will cause it to move downwardly to the right, as viewed in Fig. 1, with its bottom sliding across the ledge 62. The force of the stream flowing through the 55 inlet of the valve will also have a tendency to carry the clapper in this direction, whereby it will slide down into the pocket 14 in the cover 10 to entirely remove it from the inlet-port or orifice.

60 If there is a tendency for the clapper to be lifted with any force, as in the case of an abnormal relief of the air pressure, its outer rim will strike against the abutment or lug 63 on the cover 10 whereby to prevent the 65 clapper from up-tilting or turning over in the

direction of the outlet 4 of the valve. At the same time, the opposite rim of the clapper 15 is engaged with or rests against the curved ribs or ways 64 extending across the upper part of the interior of the valve casing 2. 70 This edge of the clapper will therefore slide along these ribs or guideways, which being in the form of a cam, will act to slide the valve laterally across its seat and downwardly into the pocket 14. In this way the valve-clapper is prevented from blocking or obstructing the flow through the outlet 4 of the valve; its release from the valve-seat and its lateral displacement thereacross being rendered more prompt and positive. As the 80 clapper 15 drops down into the pocket 14 its edge strikes against the buffer element 65, which, being of soft metal, prevents chipping or denting the rim of the clapper.

To re-seat the valve it is only necessary to 85 remove the cover 10 on the main casing 2, whereupon the clapper 60 may be lifted by its handle 48 and set back on its seat on the ring or annulus 16. In seating the clapper 15 its flange 60 is engaged with the annular outer edge of the channel 19 in the ring 16 and the clapper is then rotated back and forth to make sure that it is properly seated. After the clapper is re-seated the cover 10 is closed 90 again and the valve primed and set for operation as above explained.

It will be observed that the present improvement provides a valve of the utmost simplicity, having a minimum number of parts adapted for economical manufacture. The 100 valve-seats are embodied in the ring or annulus 16 which is made separate from the main valve body or casing 2. This provides that the valve-seats may be machined and finished apart from the casing itself, the machining 105 operations being performed on a part of relatively small dimensions in a lathe or any other suitable machine tool. Likewise, the valve clapper 15 is manufactured and machined as a separate part. This eliminates practically all machining within the valve-casing 110 except the facing off of the seat 18 against which the valve annulus 16 is bolted.

As another feature of improvement it will be noted that the valve-clapper has no hinges, 115 pivoted joints or other fitted connections to require accurate machining and adjustment within the valve-casing.

The valve-body or casing may be made as a simple casting and is of compact form and 120 minimum weight. Likewise, the seat-ring and clapper are small in dimension and light in weight so that the whole valve is further rendered more economical to manufacture.

It will be understood that while I have 125 herein illustrated a preferred embodiment of my improved valve various modifications may be made in the construction and arrangement of its parts without departing from the spirit or scope of the invention.

Therefore, without limiting myself in this respect, I claim:

1. In a differential valve, the combination of a casing having an inlet-port surrounded by an annular rim, and an unconnected floating valve-closure adapted to seat across the port and provided with a shouldered annulus engaging the surrounding rim thereof to maintain the closure in register with the port, said valve provided with an air-seat having a greater area opposed to the pressure in the valve-casing than its area opposed to the pressure through the inlet-port.
2. In a differential valve, the combination of a casing having an inlet-port opening thereinto, a sea-ring surrounding the port and provided with a recessed rim and an outer annular air-seat, a freely floating clapper adapted to seat across the port and provided with a shouldered annulus adapted to engage the rim of the seat-ring to maintain the clapper concentric therewith, and a flexible annulus on the clapper adapted to cooperate with the air-seat on the seat-ring.
3. In a differential valve, the combination of a casing having an inlet-port opening thereinto, a seat-ring surrounding said opening and provided with a central water-seat, said seat-ring also formed with an annular depression and an outer air-seat, a clapper adapted to rest across the water-seat and provided with an annular shoulder engaging the rim of the depression in the seat-ring, and a flexible annulus carried on the rim of the clapper to overhang the latter to engage with the air-seat on the seat-ring.
4. In a dry-pipe valve, the combination of a casing having an inlet-port opening thereinto, a seat-ring surrounding said port and formed with a central annular water-seat, said ring also provided with an annular channel surrounding the water-seat and an outer annular air-seat, a clapper adapted to rest across the water-seat and provided with an annular shoulder engaging the edge of the annular channel in the seat-ring, and a flexible annulus on the clapper adapted to rest against the annular air-seat on the ring.
5. In a differential valve, the combination of a casing having an inlet-port with an inclined water-seat, a free clapper adapted to seat across said port with a greater area of its surface opposed to the pressure in the casing than its area opposed to the pressure through the port, means for normally retaining the clapper in concentric relation with respect to the port, said clapper adapted to be lifted off from its seat to release its retaining means to cause it to slide laterally across the seat under the action of gravity when pressure in the casing is relieved, and an extended horizontal bearing at the rim of the seat on which the clapper rests as it slides laterally of its seat.
6. In a differential valve, the combination

of a casing having an inlet-port, a seat-ring surrounding the inlet-port and provided with an inclined water-seat, a clapper adapted to rest across the water-seat with a greater area of its surface opposed to the pressure in the casing than its area opposed to the pressure through the port, means for normally retaining the clapper in concentric relation with respect to its seat, said clapper positioned to slide laterally across the seat under the action of gravity when released from the retaining-means and a lateral ledge extending substantially tangent with the seat-ring and adapted to support the clapper resting flat thereon as it slides away from its seat.

In testimony whereof I affix my signature.
